WIDE BRUSH SECTION

Lawrence C. Herold, Lakewood, Ohio

Application June 13, 1936, Serial No. 85,085

6 Claims. (Cl. 15—181)

This invention relates to an improvement in rotary brushes and more particularly to a novel structure for a wide brush section.

Wide rotary brushes are often built up from thin individual sections assembled upon and secured to the shaft by which they are rotated. These brush sections are generally thin so that a large number of them must be assembled on the shaft to provide a brush of the length usually desired in the various industrial processes where such brushes are used. One of the objects of the present invention is to provide thicker or wider brush sections so that a smaller number need be handled in assembling sufficient brush material along a shaft to provide a brush of a given length.

Another feature of my invention is the provision of novel structural members for assembling a plurality of bristle rings into a single unit for further handling.

20 My invention also provides novel features in the mounting of bristle sections whereby mounting plates of a given size may be utilized in the formation of brush sections adapted to fit shafts of varying diameters.

25 Other novel features of my invention will be apparent from the accompanying specification and drawings and the essential features thereof will be summarized in the claims.

In the drawings, Fig. 1 is a plan view of a brush section embodying my invention; Fig. 2 is a sectional view along the line 2—2 of Fig. 1; Figs. 3A, 3B, 3C, 3D and 3E show the structure of Fig. 2 in disassembled position; Fig. 4 is a view similar to Fig. 2 showing a modification in which the relationship between the bristle rings and the side plate mountings has been varied to change the internal diameter of the section; while Figs. 5 and 6 show a modified form of brush section before and after assembly.

40 My invention relates broadly to a mounting for a plurality of bristle rings side by side in axial alignment regardless of the details of construction of the individual bristle rings. For instance in the embodiment shown, bristle rings 11 and 12 are assembled in a unitary structure by means of plate mountings but I do not desire to be limited in the particular type of bristle ring utilized in forming wide brush sections other than by the appended claims when construed in view of the 45 prior art.

The brush sections 11 and 12 each comprises a central ring 11a, 12a about which is looped bristle material 11b, 12b, which in the present instance is composed of a large number of individual bristles. However my invention contemplates

that bristle tufts or knots or other form of bristle assembly might be incorporated in my invention if desired. The combination of the rings 11a and 12a with the bristle material looped thereabout as shown in Figs. 3B and 3D I have referred 5 to hereinafter in both specification and claims as a bristle ring or brush section.

The mounting means for the bristle rings or brush sections comprises a plurality of plate members 13, 14, 15 of which the plate member 14 lies 10 between adjacent bristle rings in engagement with both of them when the brush is assembled, and the plates 13 and 15 engage the outer surfaces of the bristle rings so that the three plates provide a pair of plate members engaging each 15 side of each bristle ring with the plate 14 forming a common member of each pair. The additional plate member necessary to engage the outer surface of the second bristle ring is suitably secured to one of the side plate members forming 20 a mounting for the first bristle ring so that I build up the bristle rings by securing the mounting of one to the mounting of the other utilizing a portion of one bristle ring mounting to provide a part of the mounting for the second 25 ring. In other words, I do not simply form a plurality of bristle rings each with its individual side plate mounting members and thereafter secure them together, but I achieve the simplicity, cheapness and lightness possible by utilizing one side plate mounting to form a portion 30 of the bristle ring mounting structure for two different brush sections. Preferably the means for securing the various plate members together comprises tongues struck up from one 35 member of the pair of plates on opposite sides of a given brush section, these tongues being bent at right angles to the plate and extending toward and beyond the coating plate member and there bent down on the coating plate member to 40 clamp two plate members together on opposite sides of a brush section.

In the forms shown in Figs. 1 to 4 the securing tongues for the brush sections 11 and 12 are both struck up from the plate member 14. One 45 half of these tongues indicated at 14a are bent toward the plate member 13 and the other half 14b are bent toward the plate member 15. In assembling the brush the tongues 14a pass through the bristle material 11b to a point beyond the 50 outer face of plate member 13 to clamp the bristle material 11b between plates 13 and 14 as shown in Fig. 2. In a like manner the tongues 14b pass through the bristle material 12b beyond the outer face of plate member 15 and are then bent ra- 55

dially outward and clamped against the outer face of plate member 15 to clampingly secure the bristle ring 12 between the plates 14 and 15. This is best seen in Fig. 2.

5 By thus providing tongues bent outwardly from one of the side plate mountings of a brush section I may add to that brush section a second section by the addition of only one other side mounting plate. In the form illustrated I have thus joined 10 together two brush sections but it is obvious that by providing additional tongues on the plate member 15 extending toward the right as seen in Fig. 3E in a manner analogous to the tongues 14b, I might continue to add a third bristle ring 15 to the combination by the use of only one additional side mounting plate.

A modified form of mounting is shown in Figs. 5 and 6. Fig. 5 is an explosion view showing the parts in position for assembly and Fig. 6 20 shows the same parts completely assembled. Here plates 22 are identical annular metal rings each provided with tongues 22a struck up from their inner peripheral edges. Each ring is rotated relative to the preceding one in the series 25 so that the tongues of one ring are staggered between the tongues of the next ring in the series. Each pair of plates 22 forms a mounting for one of the brush sections 23. Obviously, as many units as desired may be secured together in this 30 manner. On the outside of the last section 24 in the series is placed a plain annular ring 25 like 15. When the brush sections are assembled as shown in Fig. 6 the tongues of each plate extend through the brush material of the adjacent brush 35 section and are bent down upon the next plate in series to hold a pair of plates together.

It will be noted in all forms of my device illustrated that the plate members 13, 14, 15 and 22 are annular in form with tongues struck up from the inner peripheral edge of one of the plate members, these tongues being extended through the adjacent brush material and bent over upon a coacting side mounting plate to clamp the brush material between two plates. It will be 40 noted that the tongues 14a, 14b and 22a also provide securing means for the rings 11a, 12a, 23a and 24a as they engage these rings upon their outer circumferences so as to position the rings 11a, 12a, 23a and 24a centrally of the plates 13, 14, 15, 22 and 25. In the modification 45 shown in Fig. 4 the tongues 14a and 14b engage the inner edge of rings 16 and 17 (which here perform a function similar to that of rings 11a and 12a) and here again the tongues provide 50 centering means for the bristle rings.

It will be noted that as between Figs. 2 and 4, the rings 11a and 12a in Fig. 2 lie radially inwardly from the tongues 14a and 14b, whereas in Fig. 4 the rings 16 and 17 lie radially outwardly of the 55 tongues. I vary the construction of my brush sections in this manner to change the internal diameter of the brush section so that the section of Fig. 2 is adapted to fit a shaft 18 of smaller diameter than the shaft 19 of Fig. 4. This variation is accomplished by making the annular plate members 13, 14 and 15 with central openings of greater diameter than the shaft to be accommodated and making the rings 16 and 17 with the same internal diameter as the openings in 60 the annular side plates where a large shaft is to be accommodated similar to that shown at 19. In this event the bristle material of the brush sections 20 and 21 where it is looped about the rings 16 and 17 radially inwardly therefrom 65 engages the shaft 19.

On the other hand, in the form shown in Figs. 1, 2 and 3, the rings 11a and 12a are of less diameter than the openings in the annular side plates but of greater diameter than the shaft 18 to be accommodated. This brings the bristle 5 material 11b and 12b farther toward the center of the brush section when the brush is assembled, as shown in Fig. 2. In other words, as compared with the structure of Fig. 4, we now have lying inwardly from the tongues 14a and 14b the thickness of the rings 11a and 12a plus the thickness 10 of the bristle material looped about these rings so that the internal diameter is reduced to fit the smaller shaft such as that indicated at 18.

It will be obvious that by substituting in Fig. 2 15 rings of proper diameter but of greater radial thickness than the rings 11a and 12a, for instance the flat rings shown at 16 and 17 but of smaller diameter, that the diameter of the final central opening of Fig. 2 could be still further 20 reduced. I am thus able to utilize side plate mounting members of a given dimension for an assembly of brush sections having different internal diameters for assembly on shafts of different diameters. 25

What I claim is:

1. In a rotary brush, two annular rings of bristles, a single plate member between said rings and engaging one side of each ring, two other plate members, one engaging the other side of 30 each ring, and means for clampingly securing said two other plate members against each ring respectively and against axial movement away from said first named plate member.

2. In a rotary brush, two annular rings of 35 bristles placed side by side and axially aligned, three plates, a single plate between said rings and directly engaging the bristles of each ring and one on the outside of each ring, whereby to form a pair of plates for mounting each ring of 40 which one plate is common to the two pairs, and means for clampingly securing each pair of plates together, said means including tongues struck up from one plate of each pair and said tongues extending toward and beyond the other plate of 45 the pair and being there bent down upon said other plate.

3. In a rotary brush adapted to be mounted on a round shaft, a pair of plates, there being central circular openings through said plates of greater diameter than said shaft, a ring having a diameter intermediate the diameters of said shaft and of said openings, bristle material looped about said ring, means for securing said plates together on opposite sides of said bristle material and for holding said ring centered in said openings, and said bristle material when looped about said ring being sufficient to fit the central opening to said shaft. 50

4. In a rotary brush adapted to be mounted on 55 a cylindrical member, a pair of annular plates, there being central openings in said plates of greater diameter than said cylindrical member, a ring of bristle material, and means holding said bristle material between said plates in a 60 manner to extend into the central openings thereof in direct engagement with said cylindrical member. 65

5. In a rotary brush, two annular rings of 70 bristles, a single plate member between said rings and engaging one side of each ring, two other plate members, one engaging the other side of each ring, tongues struck up from said first named plate member, and said tongues being bent 75 in opposite directions toward and beyond said

two other plate members and there bent down upon said two other plate members.

6. In a rotary brush, a ring, bristle material looped about said ring and extending radially outwardly therefrom, two annular plates directly engaging opposite sides respectively of said bristle material, at least one of said plates having at its inner periphery integral tongues extending substantially normal therefrom, said tongues lying 10 radially outwardly of said ring and passing

through said bristle material, and said tongues extending beyond the other plate and being there bent down upon said other plate to clampingly secure said material between said plates, whereby said ring is held against movement radially outward by said tongues and said bristle material is uninterrupted between said annular plates and radially outward therefrom. 5
